UNITED STATES PATENT OFFICE.

WILLIAM G. SHERER AND SAMUEL J. SHERER, OF CHICAGO, ILLINOIS.

DESIGN FOR A COMBINATION-COUNTER.

41,208.

Specification for Design.

Patented Feb. 28, 1911.

Application filed September 8, 1910. Serial No. 581,103. Term of patent 14 years.

To all whom it may concern:

Be it known that we, WILLIAM G. SHERER and SAMUEL J. SHERER, citizens of the United States, residing at Chicago, in the county of Cook and State of Illinois, have invented a new, original, and ornamental Design for Combination-Counters, of which the following is a specification, reference being had to the accompanying drawing, forming part thereof.

Figure 1 is a front elevation of a combi-

nation counter showing our new design. Fig. 2 is an end elevation of a combination counter showing our new design.

We claim:

The ornamental design for a combination counter as shown.

WILLIAM G. SHERER.
SAMUEL J. SHERER.
